UNITED STATES PATENT OFFICE.

FRANK SCHMIDT, OF SWANWICK, ILLINOIS.

CALF-WEANER.

1,390,061.

Specification of Letters Patent. Patented Sept. 6, 1921.

Application filed September 18, 1920. Serial No. 411,154.

To all whom it may concern:

Be it known that I, FRANK SCHMIDT, a citizen of the United States, and a resident of Swanwick, in the county of Perry and State of Illinois, have invented certain new and useful Improvements in Calf-Weaners, of which the following is a specification.

My invention relates to calf weaners, and has for its object to provide a device of this character which is of extremely simple and light weight construction and easy and inexpensive to manufacture and which will not work injury to the animal and is entirely humane in all other respects although effective in use.

Other objects and advantages of the invention reside in certain novel features of construction, combination and arrangement of parts as will be hereinafter more fully described and particularly pointed out in the appended claims, reference being had to the accompanying drawings forming part of this specification, and in which,—

Figure 1 is a perspective view illustrating the device in use;

Fig. 2 is a front elevational view thereof;

Fig. 3 is a transverse vertical sectional view on line 3—3 of Fig. 2; and

Fig. 4 is a detail perspective view of the hanger arm and a section of the hanger shaft and one of the cotter pins.

Referring to the drawings it will be seen the invention contemplates a mouth plate 10 constructed of light weight sheet metal such for instance as aluminum. The mouth plate 10 is provided at its upper end with a cut-away portion 10^a constituting a recess.

A bracket bearing 11 is arranged in the recess 10^a and centrally of the mouth plate. The bearing is constructed from a single piece of light weight sheet metal folded over on itself to provide a pair of spaced plates designated at 11^a and 11^b, respectively. The lower portion of the spaced plates 11^a and 11^b embrace the adjacent portion of the mouth plate 10, as shown in Fig. 3 and are secured thereto by rivets or similar fastenings 12 which extend through the plates 11^a and 11^b and through the mouth plate 10. The bend of the metal of which the bracket bearing is constructed is formed to constitute the bearing which is designated at 13. The portions of the spaced plates which constitute the bearing 13 are notched at spaced intervals, as indicated at 13^a and 13^b, as clearly shown in Fig. 2.

A hanger shaft 14 is rotatably mounted in the bearing 13 and consists of two sections 15 of identical construction. As shown in detail in Fig. 4, each of the sections of the hanger shaft is of semi-cylindrical construction and the sections are adapted to overlap when assembled in position in the bearing 13. Each section is provided with openings 15^a and 15^b extending diametrically therethrough and when the sections are overlapped the openings of one section are aligned with the openings of the other and in assembled position these aligned openings 15^a and 15^b are disposed respectively in the notches 13^a and 13^b of the bracket bearing. A cotter pin 16 extends through the aligned openings 15^a and a cotter pin 17 extends through the aligned openings 15^b. Both cotter pins are of identical construction. These cotter pins serve to secure the sections of the shaft together and they further serve to prevent longitudinal displacement of the rotatable hanger shaft from its bearings 13 as they are adapted to engage the vertical walls of the notches 13^a or 13^b when the shaft is moved longitudinally.

At each end the hanger shaft 14 is provided with an upwardly curved hanger arm 19, the extremity of which is provided with an enlargement 20. The arms 19 and the enlargement have their axes lying in the same plane, and these arms and enlargements extend toward each other.

In practice the enlargements 20 of the hanger arms 19 are entered into the nostrils of the animal and thus support the mouth plate 10 which depends from the hanger shaft carried by the arms. The mouth plate is freely movable on the hanger shaft as the hanger shaft is rotatably mounted in the bracket bearings secured to the mouth plate. The device may be easily applied and removed and when in use does not work injury to the animal and it is entirely humane in all respects.

I claim:

1. A device of the character described comprising a mouth plate recessed at its upper end, a bracket bearing disposed in the recess of said mouth plate and constructed of a single piece of resilient metal bent to form a pair of plates having portions embracing the adjacent portions of the mouth plate and portions defining the bearing, said portions defining the bearing being pro-

vided with spaced notches, means extending through the spaced plates and the mouth plate for securing the spaced plates to the mouth plate, a rotatable hanger shaft 5 mounted in said bearing and consisting of two semi-cylindrical sections overlapped and having their plane surfaces abutting and having alined openings disposed in said notches, a cotter pin extending through each set of said alined openings for securing 10 the sections together and preventing longitudinal displacement of the hanger shaft and hanger arms integrally formed with each end of their hanger shaft and having enlargements at their extremities adapted 15 for engagement with the nostrils of the animal.

2. A device of the character described, comprising a mouth plate, a bracket bearing secured to said mouth plate and having 20 spaced notches, a rotatable hanger shaft mounted in said bracket bearing and consisting of two semi-cylindrical sections having their plane surfaces abutting and having alined openings disposed in said notches, 25 a cotter pin extending through each set of said alined openings for securing the sections together and to prevent longitudinal displacement of the hanger shaft, and hanger arms integrally formed with each 30 end of the hanger shaft and having enlargements at the extremities adapted for engagement with the nostrils of the animal.

FRANK SCHMIDT.
